UNITED STATES PATENT OFFICE.

WILLIE B. KITTERMAN AND FLORENCE HOWLAND MILLS, OF NEW YORK, N. Y.

UTILITY BAG.

Application filed February 1, 1927. Serial No. 165,197.

This invention relates to utility bags or carrying cases particularly adapted for use by women to carry sewing, toilet articles or to be used in a variety of ways, depending upon the construction thereof.

A particular object of our invention is to provide a utility bag to which easy access is afforded and one which may be compactly folded or drawn together and stored in a minimum of space.

A still further object of the invention is to provide a novel construction of bag which can be used as a hanging case or allowed to lie flat so that its contents will be in full view and readily accessible for use.

A further particular object of the invention is to provide a utility bag of novel construction, which may be modified to serve as a wash cloth and soap holding novelty bag or may be adapted for use as a sewing implement container and also as a receptacle for holding sewing material when the same is not in use.

A still further object of the invention is to provide a utility bag which can be made of water-proof material, having a fanciful exterior and in which a rigid tray may be placed to shape the bottom of the same when it is hung up or being carried.

A still further object of the invention is to provide a hanging bag for use in travelling which may be suspended by its draw cord but, which, in its suspended position may be opened so that access thereto is had for the use of the various toilet articles, as required.

To enable others skilled in the art to fully comprehend the underlying features of our invention that they may embody the same in the various modifications in structure and relation contemplated, a drawing depicting a preferred form has been annexed as a part of this disclosure and in such drawing, similar reference characters denote corresponding parts throughout all the views, of which,

Figure 1 is a view in perspective of a form of bag used to hold soap and a wash cloth, the same being shown in its closed position.

Figure 2 is a view in perspective of the bag shown in its partly opened position.

Figure 3 is a view similar to Figure 2 but showing the side flaps of the bag opened and also the wash cloth holding strap, which forms a part of the receptacle, opened so that the wash cloth may be removed from its position.

Figure 4 is a view in perspective showing the soap holding receptacle open disclosing

the interior soap holding tray in position.

Figure 5 is a top, plan view of the bag, the wash cloth holding strap being shown closed.

Figure 6 is a sectional view taken on the line 6—6 of Figure 5 showing the construction of the bag.

Figure 7 is a view in perspective of a bag arranged to hold sewing or toilet articles, the same being shown in its position when not in use, and suspended by its draw string.

Figure 8 is a view in perspective of the bag as shown in Figure 7, after the end flaps thereof have been opened.

Figure 9 is a view in perspective showing how the end flaps may be joined with one of the side flaps to provide a suspended receptacle for toilet goods when the same is desired to be used when suspended.

Figure 10 is a top, plan view of the bag shown in Figure 9, illustrating the shape and arrangement of the end and side flaps and also of the tray holding casing embodied therein, and

Figure 11 is a sectional view taken on the line 11—11 of Figure 10 showing the construction of the bag.

Referring to the drawings in detail, the bag in general, as used to hold soap and a wash cloth is indicated by the numeral 5 and is cut to provide the side flaps 6 and end flaps 7, in the latter of which is provided, the draw string holding flutes 8 through which pass the draw strings 9. The material from which the bag is made may be of cretonne or some other fancy fabric which forms the outer part thereof, which is suitably lined with rubber or other water-proof material, the two materials being joined by sewing or gluing or in any other satisfactory manner. The outer ends of the side flaps 6 are provided with the mating members of snap fasteners 10 as are also the edges of the end flaps in their mid portion. The snap fasteners are indicated in this latter instance by the numeral 11. At the center of the bag, we provide a flexible casing 12 which is made from water-proof material and is secured at its bottom edge as at 13 in any suitable manner to the bag material 14. This casing is provided at one side with a cover 15 which may be cut integral with the casing 12 or may be secured thereto in any manner, such as cementing and may be made of the same water-proof material from which the casing is made. This cover 15 is provided on its ends

with the straps 16 which carry the mating

members of a snap fastener 17 and it is evident from an inspection of Figures 4 and 6 that a rigid tray 18 may be positioned in the casing 12 to receive a cake of soap and may be enclosed by the cover 15 which, through the medium of its strap 16 is adapted to receive and hold a wash cloth 19, as shown in Figure 3. Immediately after the soap is used, it is wet, of course, and when once placed into the receptacle 18 is prevented from soiling any other part of the bag by reason of the fact that the casing 12 and the cover 15 are made of water-proof material and in order to hold the cover 15 closed, the side flaps 6 are drawn over the receptacle and are held closed by the snap fasteners 10 as shown in Figure 2, after which the snap fasteners 11 may be united to hold the bag at its mid portion closed, so that the contents thereof cannot fall out and also so that the dampness or drippings from the wash cloth, cannot leak out nor escape from the closed bag, it of course being understood that the draw strings 9 can be tied or otherwise drawn upon to close the upper ends of the end flaps 7 to present the appearance, illustrated in Figure 1.

As will be noted from the foregoing description, the rigid tray member forms the bottom of the bag and gives the same shape when it is held up in suspended position and in further utilizing this particular feature, we have embodied in a bag of slightly different construction, but embodying the same principle, a toilet article holding tray 20, as illustrated in Figure 9 which is held in position in the center of the toilet bag 21 or utility bag; as it might better be termed, through the medium of a casing 22 similar to that hereinbefore described for holding the soap tray; but in view of the fact that, with slight modifications, the tray might be used for another purpose, we have shown in Figure 7, a bag which is arranged to be used as a sewing bag and which consists of the tray 20 positioned in a suitable casing 22 which is secured to the bag material 21 at the center thereof and in position to be overlapped or closed by the side flaps 23 which may or may not be provided with pockets 24, depending upon the use to which the bag is to be put. For instance, in the sewing bag, the flaps 23 might be provided with the pockets 24 or might be used without, so that they could be folded over as shown in Figure 8 to provide a cover for the tray, which would hold the sewing material, such as needles, threads and the like. The flaps 23 provide a bottom for the bag when closed up in the position illustrated in Figure 7 to hold the material to be sewed upon. In either event, the bag consists of the flaps 23, having at their outer edges the snap fasteners 25, one of which is provided at each corner of the outer edge of the flaps 23 so that when the same are folded to

the position as shown in Figure 8, the snap members 25 will retain them in their closed position. The bag is also provided with end flaps 26 which may be cut in any careful manner and which, in their ends, are provided, as before described, with the draw string flute 27 through which pass the draw strings 28, the flaps 26 being provided on their edges, at the mid portions thereof with the snap fasteners 29 and adjacent one side 70 of their outer edge or end with the snap fasteners 30, the purpose of which will be hereinafter described. In the use of the bag for the holding of sewing, the flaps are thrown in and fastened as shown in Figure 8 and 80 then the snap fasteners 29 are secured together to give the appearance illustrated in Figure 7. This fastening of the snap fasteners 29 provide a receptacle, as before set forth, in which may be carried the material to be sewed upon. However, when the bag is to be used for the carrying of toilet articles as when travelling, the casing 22 may be provided with side straps 31, into which may be inserted the tooth brush holding member 32. 90 When the bag is in use when travelling, the bag is suspended by the draw strings 28, as illustrated in Figure 9, and in order to maintain the bag in open position, as shown in such illustration, the snap fastener 25 on one 95 of the flaps 23 are secured to the snap fasteners 30 which are incorporated in the end flaps 26. This will give the bag the appearance shown in Figure 9 and the front portion thereof being wide open, will allow easy access to the material held in the tray 20, as is evident. In the pockets 24 there may be carried an additional envelope 32, if desired, the pocket flaps 33 being secured in closed position, through the medium of the snap fasteners 34 provided therein. It is evident in this construction also, that the tray 20 shapes the bottom of the bag and in fact, forms the bottom thereof and, if desired, the bag illustrated in Figure 9 can be suspended in the position shown in Figure 7 so 100 that the bag may be used to hold toilet articles and sewing at the same time, or it may be used for either purpose separately. It is important, however, that it be understood 110 that the bag illustrated in Figure 8 may be drawn up to the position shown in Figure 7 and in Figure 9 with but different fastenings of the snap fasteners 29 and 30 and no modification in structure need be made to adapt 120 the bag for the purpose of carrying sewing or carrying toilet articles.

It is evident therefore, that we have provided an improved utility bag which may be used as a soap and wash cloth container or one which may be adapted for use as a travel case to contain toilet articles or other accessories, also we have provided a utility bag which may be used as a beach bag, a sewing bag, a boudoir case, a laundry bag, a manicure 130

bag, a vanity bag and which can be used in its suspended position or placed upon a support and opened out so that the contents are readily accessible. The material from which the bag is made may be rubberized silk, cretonne or any other suitable water-proof or lasting material, particularly adapted for the purpose for which the bag is to be used, for instance, leather, satin, or silk.

10 While we have illustrated and described our invention with some degree of particularity, we realize that in practice various alterations therein may be made. We therefore reserve the right and privilege of changing 15 the form of the details of construction or otherwise altering the arrangement of the correlated parts without departing from the spirit of the invention or the scope of the appended claims.

20 Having thus described our invention what we claim as new and desire to secure by United States Letters Patent is:—

1. A container comprising a piece of material, pairs of oppositely disposed flaps 25 formed thereon, a receptacle so positioned on the piece of material that the flaps may be drawn thereover to cover the same, draw strings in one pair of the oppositely disposed flaps for holding the same together, 30 fasteners in the other pair of flaps for holding the same closed, and the draw strings providing an arrangement whereby the container may be suspended.

2. A container comprising a piece of fabric, 35 a casing made of fabric attached to the material at the center thereof, a rigid tray in said casing, the tray and the casing constituting a

bottom for the container, pairs of oppositely disposed flaps formed in the material and arranged to be folded in over the tray to provide a cover therefor, snap fasteners on one pair of said flaps for fastening the same together, and draw strings in the other pair of flaps for drawing the same together.

3. A container comprising a piece of fabric, 40 a tray holding casing, of fabric disposed at the center thereof, a rigid tray in said casing, end and side flaps formed on said piece, snap fasteners in the side flaps for maintaining the same in closed position over the tray, 45 snap fasteners in said end flaps and so arranged that when fastened together the end flaps will be drawn up to form an additional receptacle above said tray and means for drawing the ends of said end flaps together.

4. A container comprising a piece of fabric, 50 a lining of water-proof material, a tray-holding casing of fabric disposed at the center thereof, a rigid tray in the casing, end and side flaps formed in said piece, snap fasteners in the side flaps for retaining the same in closed position over the tray, snap fasteners in said end flaps so arranged that when fastened together, the end flaps will be drawn up 55 to form an additional receptacle above said tray and draw strings for drawing the ends of said end flaps together, the draw strings serving as a means through which the container may be hung up.

In testimony whereof we affix our signatures.
